UNITED STATES PATENT OFFICE.

FRANK J. COULIERES AND ROBERT H. BELLMAN, OF NEW KENSINGTON, PENNSYLVANIA.

CONVEYER.

1,186,284.

Specification of Letters Patent. Patented June 6, 1916.

Application filed April 9, 1915. Serial No. 20,121.

To all whom it may concern:

Be it known that we, FRANK J. COULIERES, a subject of the King of Greece, and ROBERT H. BELLMAN, a citizen of the United States, 5 residing at New Kensington, in the county of Westmoreland and State of Pennsylvania, have invented certain new and useful Improvements in Conveyers, of which the following is a specification.

10 This invention relates to conveyers, particularly adapted for the transportation of metallic sheets or plates, and has for its object to provide a conveyer in a manner as hereinafter set forth with means for conveying metal plates while in a standing or upright position for the purpose of cooling them and to further provide the conveyer with means for transporting the cooled plates through a flour box and then discharging them upon a track for transportation.

15 Further objects of the invention are to provide a conveyer for the purpose set forth which is comparatively simple in its construction and arrangement, strong, durable, efficient and convenient in its use, and comparatively inexpensive.

20 With the foregoing and other objects in view the invention consists of the novel construction, combination and arrangement of parts as hereinafter more specifically described and illustrated in the accompanying drawings, wherein is shown an embodiment of the invention, but it is to be understood 25 that changes, variations and modifications can be resorted to which come within the scope of the claims hereunto appended.

25 In the drawings wherein like reference characters denote corresponding parts throughout the several views:—Figure 1 is a side elevation of a conveyer in accordance with this invention. Fig. 2 is a top plan view, Fig. 3 is a detail of the conveyer element, Fig. 4 is a top plan, broken away, 40 of a supporting bracket for the sheet or plate.

30 Referring to the drawings in detail the conveyer includes a supporting frame consisting of pairs of parallel uprights 1, 2, 3 and 4 and the pairs of uprights are spaced from each other. The uprights of the pair 3 are of greater height than the uprights of the pairs 1, 2 and 4 and the uprights of the pair 4 are of less height than the uprights of 35 the pair 3. The uprights of said pairs of

uprights are arranged in alinement and connected together by longitudinally extending members 5, 6, which are in the form of angle bars and are secured in position by hold fast devices 7. The members 5 and 6 are positioned below the tops of the uprights of the 45 said pairs. The uprights of the pairs 3 and 4 are connected together by longitudinally extending angle irons 8 arranged above the members 5 and 6. The angle irons 8 are positioned below the tops of the uprights of the pair 3. The angle irons 8 constitute supports to be presently referred to. The uprights of each pair are spaced from each other and the upper ends of the uprights of the pairs 1 and 2 are provided with bearings 9 and 10, respectively. Mounted in the bearings 9 of the uprights of the pair 1 is a shaft 11 provided with a pair of sprocket wheels 12, and mounted in the bearings 10 of the uprights of the pair 2 is a shaft 13 provided with a pair of sprocket wheels 14. Mounted upon the members 5 and 6 are bearings 15 and journaled in the said bearings is a shaft 16, carrying a pair of sprocket wheels 17. Traveling over the sprocket wheels 12, 14 and 17 is a conveyer element consisting of a pair of endless sprocket chains 18 which are connected together by spaced transverse bars 19, each carrying a U-shape supporting 50 bracket 20, formed with a supporting ledge 21. The arms of each of the brackets 20, which are indicated by the reference character 22, have rearwardly extending brace members 23 which are connected as at 24 to 55 the chains 18. The supporting brackets 20 are secured to the chains 18 in a manner whereby they will be disposed at an inclination with respect to the line of travel of the 60 conveyer element and by such an arrangement when the conveyer element is transporting metal sheets or plates these latter will be maintained in an inclined position and the said conveyer element is employed for the purpose of transporting the plates to 65 cool them.

65 The pair of uprights 2 are of slightly greater height than the pair of uprights 1 whereby sprocket wheels 14 will be positioned slightly above the sprocket wheels 12 so that the conveyer elements when traveling at the top of the machine will move upwardly at an inclination. A motor or other suitable prime mover is coupled with the shaft 16 for driving it under such condi- 70

tions imparting travel to the conveyer element in view of the fact that the sprocket wheels engage in the sprocket chains. The metallic sheets or plates are supplied to the conveyer element manually.

Secured to the uprights of the pair 3, near the top thereof, is a support 24^a, provided with shafts 25, 26, carrying pulleys 27 for operating the conveyer element 28 which is of less width than the distance between the arms 22 of the bracket 20 and the said conveyer element 28 has one end extended in proximity to the chains 18 whereby said element 28 can receive from the bracket 20 a metallic sheet or plate when the bracket is in the position as shown at 29, Fig. 1. The shaft 13 is extended, as well as the shaft 26, and the said shafts 13, 26 are operatively connected together by a transmission belt 30 whereby when the shaft 13 is operated motion will be imparted to the shaft 26 and the conveyer element 28 operated. The conveyer element 28 is formed in two sections as illustrated in Fig. 2.

Mounted upon the tops of the uprights of the pair 3 are bearings 31 and journaled in said bearings is a shaft 32. Carried by the angle irons 8 are supports 33, provided with bearings 34, in which is journaled a shaft 35, the latter being extended and operatively connected to the shaft 26 by a transmission belt 36. The shafts 32 and 35 are provided with sprocket wheels 37 and engaging said sprocket wheels 37 are a pair of endless sprocket chains 39, carrying shifting elements 40 and the function of the shifting elements is to engage the plate or sheet transported by the conveyer 28 and shift the same through a flour chamber 41, the latter being provided with a table 42, upon which the plate or sheet is shifted. Arranged within the flour chamber 41 is a pair of brushes 43, which are operatively connected together, and one driven by a transmission belt 44 which is associated with the shaft 35. At the front of the chamber 41 spaced guides 45 are provided to prevent the bucking of the sheet.

Arranged upon the angle irons 8, in front of the guides 45, is a conveyer device consisting of a frame 46 and a pair of superposed conveyer rolls 47, a pair of superposed conveyer rolls 48 and a pair of guides 49, these latter being positioned between the pairs of rolls 47 and 48. Guides 49 prevent the sheet or plate from bucking when operated on by the rolls 47, 48 for the purpose of conveying the sheet to a counter-balanced pivoted table 50, carried by a support 51. The shafts of the upper rolls of the pairs of rolls 47, 48 are indicated at 52, 53, and operatively connected together by a belt 54 and the shaft 52 is operatively connected to the shaft 35 by a transmission belt 55.

The reference character 56 denotes a sup-

porting frame, carrying a track 57, upon which travels a truck 58 and the latter is arranged below the table 50 and is adapted to have the metallic sheets dumped thereon whereby the sheets can be transported to any point desired.

What we claim is:

1. A conveyer for the purpose set forth comprising a conveyer mechanism for transporting metallic sheets in an upright position, means for receiving the sheets from said conveyer mechanism, a flour room arranged in the path of the travel of the sheets and having means for cleaning the sheets when shifted there-through, means for shifting said sheets from said receiving means through said flour means, and a combined sheet receiving and dumping means for the reception of the sheets from the said flour room, and means for transporting sheets from the flour room to said combined receiving and dumping means, said conveyer mechanism including spaced permanently inclined U-shaped supporting brackets for the metallic sheets, and said receiving means of less width than said brackets to take up the sheets thereof during the operation of the conveyer.

2. A conveyer comprising a conveyer mechanism including inclined supports for maintaining metallic sheets at an inclination during the operation of said mechanism, a receiving means for taking up the metallic sheets from said supports during the operation of said mechanism, a flour room associated with said receiving means and adapted to have the sheets shifted there-through and further adapted to have means for cleaning the sheets when shifted there-through, traveling shifting elements arranged above said receiving means and capable of engaging the plates taken up by said means for shifting them through said flour room, and means for transporting the plates after passing through said flour room on a truck.

3. A conveyer comprising a conveyer mechanism including inclined supports for maintaining metallic sheets at an inclination during the operation of said mechanism, a receiving means for taking up the metallic sheets from said supports during the operation of said mechanism, a flour room associated with said receiving means and adapted to have the sheets shifted there-through and further adapted to have means for cleaning the sheets when shifted there-through, traveling shifting elements arranged above said receiving means and capable of engaging the plates taken up by said means for shifting them through said flour room, and means for transporting the plates after passing through said flour room on a truck, said transporting means including a dumping element for discharging the plates onto a truck.

4. A conveyer comprising a conveyer element including spaced permanently inclined U-shaped supporting brackets for maintaining metallic sheets in a standing position
5. when transported by said conveyer element, means for taking up said metallic sheets from said supporting elements during the operation of the conveyer elements, and means for shifting the plates off from said
- 10 take up means and into a flour room, a room adapted to have means for cleaning plates and associating with said shifting means, said

shifting means moving said plates through said flour room to clean the plates, and means for transporting the cleaned plates on a suitable support. 15

In testimony whereof we affix our signatures in presence of two witnesses.
